Primary Examiner — Katherine Glennon(74) *Attorney, Agent, or Firm* — Jeffrey Schox; Caitlin Ploch(57) **CLAIM**

I claim the ornamental design for a haptic wristband, as shown and described.

DESCRIPTION

FIG. 1 is an elevation view of the front of a haptic wristband. FIG. 2 is an elevation view of the back of the haptic wristband.

FIG. 3 is an elevation view of the left of the haptic wristband.

FIG. 4 is an elevation view of the right of the haptic wristband.

FIG. 5 is a plan view of the top of the haptic wristband. FIG. 6 is a plan view of the bottom of the haptic wristband. FIG. 7 is an isometric view, from the back left, of the haptic wristband; and,

FIG. 8 is an isometric view, from the front right, of the haptic wristband.
